UNITED STATES PATENT OFFICE

CLARK T. MORSE, OF DETROIT, MICHIGAN, ASSIGNOR TO AMERICAN BLOWER CORPORATION, OF DETROIT, MICHIGAN, A CORPORATION OF DELAWARE

STEEL PIPE AND FIN HEATER

Application filed October 26, 1931. Serial No. 571,096.

This invention relates to improvements in radiators, and has for its object to provide a radiator in which the headers are cut back so that sections of the radiator can be joined together without there being any appreciable amount of space between the sections forming the complete radiator structure.

It is an object of this invention to provide a radiator section consisting of heads united by pipes, across which fins are arranged for heat radiation and distribution. The parts of the heads are formed of sheet material such as sheet steel, and are welded together to form the heads, to which the pipes are also welded.

It is also an object of this invention to provide radiator sections in which the heads have cut-back portions, into which connecting nipples may be inserted for connecting the sections of the radiator to form a complete radiator of one continuous structure, with no space therebetween.

It is a further object to provide guard means on the ends of the sharp heat radiating steel plates so that the radiators can be lifted without injury to the operator, as these radiators are of considerable weight and without these guards it would be dangerous to handle them.

It is a further object to provide a novel header construction of lesser width than the general width of the radiator and integrally formed with the heating pipes, as well as rigidly connected to adjacent sections of the radiator.

These and other advantages will appear from the following description taken in connection with the drawings.

Referring to the drawings:

Figure 1 is a side elevation showing two radiator sections united to form a single radiator unit.

Figure 2 is a section on the line 2—2 of Figure 1.

Figure 3 is a view showing the upper ends of two radiator sections, with a part of one radiator section in section to show the nipple construction.

Figure 4 is a view taken on the line 4—4 of Figure 3.

Each heater section is composed of an upper header, a lower header, connecting pipes and radiating fins supported by the pipes between the headers. Each header is composed of a curved or wrapped plate 1, a flat tube plate 2, welded to the curved or wrapped plate and to which the ends of the tubes are welded. The two plates are welded to form an arch-shaped passageway, having a flat bottom, the sides and top of which are formed by the wrapped plate 1, while the bottom or flat part is formed of the plate 2. When the header is used at the lower end of the radiator section or radiator unit the parts are reversed from what they are at the upper end thereof.

The wrapped plate is shorter than the horizontal or tube-supporting plate 2. However, the side of the wrapped plate adjacent the plate 2 is of the same length as the plate 2. At each end of the header is an end member 3 having a lateral and outwardly inclined projection 4. This end member with the projection 4 completely incloses one end of the header and two of these end members and projections inclose both ends of the header. Each end member is attached to the plates, both 1 and 2, by means of welds 5 so that these parts, when finished, are integral one with the other so the header is formed of one continuous piece of metal.

When the end members have been welded to the plates there is left a cut-back portion 6. This is due to the fact that the main body of the header does not extend the full width of the radiator but is cut short of the full width of the radiator to provide space for a nipple 8 which has threads on each end, right and left hand respectively.

These nipples are used for uniting sections of the radiator, and in doing this each end of the nipple is threaded into a threaded opening or hole 7 in the end member 3. Two of these nipples are used for binding two sections of the radiator, as shown in Figure 1. While only two of these sections are shown thus united in Figure 1 any number may be so joined, so that a radiator of any length may be provided, the only thing necessary to unite the two sections being to insert the

nipple in the cut-back parts and rotate the nipple so that the threads on the ends of the nipple will engage the threads in the holes in the end members. And in order that the 5 nipple may operate to connect the two adjacent sections the threads on the ends of the nipple are oppositely threaded, and the threads in the end members are made to correspond with the threads on the nipple.

10 The foregoing is a description of the construction of the head and the manner in which two headers may be united so that radiator sections may be united.

In order to form a complete radiator section two headers are united by means of 15 tubes 9. Each end of each tube projects through a tube header plate and is welded thereto, as indicated by the numeral 10. These tubes may be of any convenient shape.

20 As shown in Figure 4 they are oval. Supported by these tubes and in parallel relationship to the header tube plates are steel fins 11 formed from thin steel plates. These fins have holes therein to receive tubes.

25 At the ends of certain of the plates and attached to the sides thereof are reenforcing plates 12, which are welded or otherwise permanently attached to the sides of the fins. The purpose of these plates is to form a support for a cover plate 13 fitting over the ends of the radiator fins. The cover plate has lateral flanges 14, which are attached to the re-enforcing plates and to the fins by means of 30 bolts 15. There may be any desired number 35 of these bolts and reenforcing plates.

The radiator is heated by means of some heating fluid, which is admitted to the radiator by means of a pipe 16 and discharged therefrom by means of a pipe 17. The heating fluid goes into the radiator at one end and passes down through the pipes into the header at the other end.

40 This radiator is so constructed that either end may be used as the top or bottom part 45 of the radiator, both headers being identical. A radiator constructed in the manner herein set out is strong, durable and is well adapted for use in manufacturing plants, power houses and the like where a large quantity of 50 radiating surface is needed, and where, in order to supply this surface, a rigid structure must be provided.

55 This rigid structure is afforded by means of applicant's header structure, composed essentially of a one-piece sheet of hollow metal such as is formed by bending and properly shaping plates of steel and welding the plates together to form a header. Two of these headers united by pipes form a rigid, 60 strong and durable section unit, any number of which may be connected in the manner shown in Figures 1 and 3. Stress is particularly laid on the fact that all parts are welded. There are no bolts or rivets with the exception of bolts for holding the cover plate

in position. This plate is merely to protect the hands of the workman when moving or installing the units.

It will be understood that I desire to comprehend within my invention such modifications as come within the scope of my claims and my invention.

Having thus fully described my invention, what I claim as new and desire to secure by Letters Patent, is:

1. A radiator consisting of a plurality of radiator sections, each section consisting of a pair of headers cut away at each end to provide space for a nipple, and a nipple connecting two headers of two adjacent sections located in the spaces thereof so that the sections may fit close together. 80

2. A radiator consisting of a plurality of radiator sections, each comprising a pair of headers connected by pipes, and nipples joining each header to a header of an adjacent section, each header being formed to provide space for the nipple so that adjacent sections joined by the nipple may fit close together. 85

3. In a radiator consisting of sections, a pair of headers for each section, a plurality of pipes connecting the headers, and means connecting each header of one section to a header of another section and forming a passageway between the headers, said headers and said means being so formed that when the headers are connected by said means the sections will fit close together. 90

4. In a radiator consisting of sections, a pair of headers for each section, each header having at each end a cut-back portion, pipes connecting said headers, fins on said pipes, and means in the cut-back portions connecting each header of one section to a header of another section and forming a passageway between the headers, said headers and said means being so formed that when the headers are connected by said means the ends of the fins of one section will be closely adjacent the ends of the fins of the other section. 105

5. In a radiator consisting of sections, a pair of headers for each section, each header consisting of an arch-shaped plate, a pipe plate and a pair of end members welded to one another, pipes welded to the pipe plates and forming connections between the headers, each end of each header being cut away on the arched side to form a nipple space, 115 and a nipple connecting each header of one section to a header of another section and fitting in the cut-away parts in the headers so that the sections may abut each other. 120

6. In a radiator consisting of sections, a pair of headers for each section, each header consisting of an arch-shaped plate, a pipe plate and a pair of end members welded to one another, pipes welded to the pipe plates and forming connections between the headers. 125

ers, fins on the pipes, each end of each header being cut away on its arched side to form a nipple space, and a nipple connecting each header of one section to a header of another section and fitting in the cutaway parts of the headers so that the ends of the fins of one section abut the ends of the fins of another section.

7. In a radiator consisting of sections, a pair of headers for each section, each header having at each end a cut-back portion, pipes welded at each end to any of said headers and forming passageways between the headers, fins on the pipes parallel to the headers, and means in the cut-back portions to attach each header of one section to a header of another section and form a connecting passageway, said headers and means being so formed that the fins of one section are closely adjacent the fins of another section.

8. In a radiator, a plurality of pipes for conducting a heating fluid, a plurality of rectangular fins on said pipes, supporting plates attached to the edges of certain of said fins at their ends, and protecting plates on the ends of said fins supported by the supporting plates.

9. In a radiator, a plurality of pipes for conducting a heating fluid, a plurality of heating fins on said pipes, supporting plates welded to said fins, protecting plates for said fins, and means for attaching the protecting plates to the supporting plates.

10. In a radiator, a plurality of pipes for conducting a heating fluid, a plurality of heating fins on said pipes, supporting plates welded to said fins, protecting plates for said fins, and means extending through the plates for supporting the protecting plates and holding them against the fins.

11. In a radiator, a plurality of pipes for conducting a heating fluid, a plurality of rectangular heating fins on said pipes, supporting plates welded on the edges of certain of said fins at their ends, protecting plates extending over the ends of said fins, said protecting plates having flanges engaging the supporting plates, and bolts extending through the flanges and the supporting plates to support the protecting plates.

12. In a radiator, a pair of headers connected by pipes, fins on said pipes, supporting plates on the side edges of certain of said fins, protecting plates on the ends of said fins, each protecting plate having its edges bent to form flanges fitting along the side edges of the fins and along the supporting plates, and bolts extending through the flanges and the supporting plates to support the protecting plates.

13. In a radiator, a pair of headers, each comprising a pair of plates, one flat and the other arcuate with its edges welded to the edges of the flat plate, each flat plate having holes therein, pipes connecting the headers

with their ends in the holes and welded to the flat plates, fins on the pipes, and protecting plates supported on the ends of the fins.

14. In a radiator, a pair of headers, each comprising a pair of plates, one flat and the other arcuate with its edges welded to the edges of the flat plate, each flat plate having holes therein, pipes connecting the headers with their ends in the holes and welded to the flat plates, fins on the pipes, and protecting plates supported on the ends of the fins, each protecting plate having flanges engaging the side edges of the plate.

15. In a radiator, a pair of headers, each comprising a pair of plates, one flat and the other arcuate with its edges welded to the edges of the flat plate, each flat plate having holes therein, pipes connecting the headers with their ends in the holes and welded to the flat plates, fins on the pipes, supporting plates attached to the sides of certain fins at their ends, protecting plates engaging the ends of the plates and having flanges engaging the supporting plates, and means for attaching the flanges to the supporting plates.

16. In a radiator, a pair of headers, each comprising a pair of plates, one flat and the other arcuate with its edges welded to the edges of the flat plate, each flat plate having holes therein, pipes connecting the headers with their ends in the holes and welded to the flat plates, fins on the pipes, supporting plates attached to the sides of certain fins at their ends, protecting plates engaging the ends of the plates and having flanges engaging the supporting plates, and bolts for attaching the flanges to the supporting plates.

17. In a radiator, an end header plate, tubes carried thereby, a header inclosure over the open ends of the tubes of lesser length than the length of the radiator, and set-back end members on said plate closing the ends of the header inclosure remote from the sides of the radiator.

In testimony whereof, I affix my signature.
CLARK T. MORSE.
